ASH-TRAY HOLDER

Application filed August 20, 1928. Serial No. 300,660.

Our invention relates to a portable ash-tray holder for the class of ash-trays used by smokers for depositing ashes of cigars, cigarettes or pipes and which holders also may have means for holding unconsumed cigars, cigarettes and also means for holding a match box.

The main object is to provide a simple, efficient and easily adjustable device for ash trays by means of which the latter may be mounted in convenient position of any vertical, elongated object such as the stem of a portable reading lamp or other upright elongated object.

15 In the accompanying drawing,—

Fig. 1 is an elevation of a so-called electric floor lamp and one of our ash-tray holders in operative position on the stem or column thereof.

20 Fig. 2 is a plan view of our device in enlarged scale, and a column to which it is attached.

Fig. 3 is an edge view of the holder in Fig. 2 slightly modified.

25 Referring to the drawing by reference letters, we have illustrated in Fig. 1 a floor lamp comprising the usual base A in which is fixed an upright column B at the upper end of which is suitably fixed illuminating means

30 within a shade C to cast light down for reading purposes. It is well known that many persons use such lamps while reading and simultaneously smoking tobacco in some form and necessitating the use of an ash try. Our

35 device is designed to mount an ash tray near the smoker-reader on a fixed object such as the column or pedestal of the reading lamp in which case the said tray is of course convenient and readily accessible to the person or persons near such lamp or other object.

40 Therefore B may represent any convenient upright object near the user of the ash-tray a floor lamp being illustrated as a desirable object for the reasons stated.

45 Ash trays as a general rule are of dish shape D with the usual upper perimetral flange D'' (Fig. 1) on which may be fixed a cigar holder D² and any suitable type of match box holder D³. Our device comprises

50 a band-metal hoop E of a size to snugly 55 close the dish-part of an ash tray with the flange of the latter resting on the upper edge of said hoop or band. At one side of hoop E the metal band is formed with outwardly directed parallel arms E², from the outer parts of which the bands are bent inwardly toward each other in curvatures E³, thence diagonally and inwardly toward each other in shallow V-shape formation E⁴, to a converging point E⁵ outwardly of the hoop formation E. The band metal may be of any suitable width. F is a fastening strap preferably of good pliable material or spring brass with one end part fixed to an arm E² as at G in Fig. 2. This strap has a row of holes H toward its free end in any of which may be inserted a thumb-screw J (Figs. 1 and 2) the threads of which may then be engaged in the threads of a tapped hole K in or near the other curvature E³ of the band frame. There 60 may be one, two or more holes K. In mounting the device to frictionally engage a small diameter upright, as shown cross-hatched in Fig. 2, strap F is simply passed behind the upright to inclose it between said strap and in 65 the V-shaped part of the frame; thus making three point contact with the upright. The thumb screw is simply inserted in one of the holes H when the strap is spaced some from 70 an adjacent hole K in which the screw is engaged and drawn into until the strap is drawn taut and clamps the device securely to the upright. In Fig. 2 is also illustrated in dotted lines how a comparatively large upright may be likewise engaged, and it will also be readily 75 understood that a square or polygonally shaped column may be just as efficiently engaged by allowing one of the angular edges to be engaged in the V-shaped part and the strap otherwise used in like manner about 80 the column.

85 We claim:

In a holder for trays of dish like form with an upper perimetral flange; a metal loop frame adapted to encircle such tray under its flange, 90 a pair of integral parallel arms extending from said loop outwardly, thence bent inwardly toward each other and joined in a shallow V-shape formation pointed toward the center of the loop, an adjustable, flexible 95 100

strap fixed to one of said parallel arms and means for engaging and pressing the free end of said strap toward the other of said parallel arms to clamp an upright object between said strap and the V-shaped part of the frame.

In testimony whereof we affix our signatures.

FRANK J. CHESLOCK.
CLEMENT A. YARES.
